UNITED STATES PATENT OFFICE

JOHN H. FOX, OF PITTSBURGH, PENNSYLVANIA, ASSIGNOR TO PITTSBURGH PLATE GLASS COMPANY, A CORPORATION OF PENNSYLVANIA

GLASS SURFACING APPARATUS

Application filed May 27, 1930. Serial No. 456,234.

The invention relates to apparatus for surfacing glass sheets and the like, and particularly to such apparatus as is employed in a continuous plate glass surfacing operation. In an operation of this kind, the glass sheets are carried on tables or cars arranged in a continuous train which passes beneath a series of grinding and polishing machines. It is highly desirable in the use of this apparatus that the tracks should be kept in exact alignment and also the machines themselves; otherwise breakage occurs due to irregularity in the operation of the cars and the surfacing machines. The object of this invention is to provide a construction which is very rigid and not subject to any disturbance of the structure in which the apparatus is housed; and in which the tracks and machines can be lined up at any time without difficulty and without any interruption in the operation of the plant. Certain embodiments of the invention are illustrated in the accompanying drawings, wherein:

Figure 1 is a vertical section through the apparatus and the building housing it. Figs. 2 and 3 are sections on the line II--II and III--III, respectively of Fig. 1. Fig. 4 is an enlarged detail section. Fig. 5 is a section on the line V--V of Fig. 4. Fig. 6 is a detail section showing the track adjusting means of Fig. 6. Fig. 7 is a plan view of the device of Fig. 6. Fig. 8 is a side elevation indicating a modification of the track adjusting means. And Fig. 9 is a detail section showing a modification of the structure shown in Fig. 4.

Referring to Figs. 1 and 2, the building in which the apparatus is housed comprises the side walls 1, 1 and the roof 2 carried by the transverse trusses 3. Extending longitudinally of the building are the pairs of tracks 4, 4 on which are mounted the series of tables 5, 5 carrying the sheets to be surfaced. Suitable means are provided for moving the cars along the tracks in a continuous train, such means including driven pinions engaging tracks 6, 6 on the bottom of the cars, this being a car-driving means well known in the art. Mounted in series longitudinally of the track above the cars or tables 5 is a series

of surfacing machines 7, 7, such surfacing machines comprising grinding machines and polishing machines, the machines shown being grinding machines. These machines comprise runners 8 driven from motors 9 through the intermediary of suitable reduction gearing, the particular construction of these machines constituting no part of the present invention and being fully shown and described in the Evans Patent No. 1,577,457.

The tracks and the machines are all carried by a framework which extends the length of the system and is entirely independent of the structure of the building. This framework comprises the transverse girders 10 carrying the track girders 11, the pillars 12, the transverse beams 13 and 14, and the longitudinally extending tie girders 15, 16 and 17, all rigidly secured together at the intersections of the beams and the girders.

This framework is supported upon a foundation 18 preferably of reinforced concrete which is shown as carried by the piling 19. Between the foundation and the framework are a plurality of cast steel stools 20, these stools being arranged in series transversely of the framework, as indicated in Fig. 1, and longitudinally thereof, as indicated in Figs. 2 and 3, the stools being anchored to the concrete by means of the foundation bolts 21. Carried by each stool is a pair of jacks 22, 22, whose lifting members engage the plates 23 beneath the girders 10. This provides a means for raising or lowering the framework which carries the machines and the track at any point which may require alignment. On each side of the jacks is a pair of wedges 24, 24, which act as blocking-up means to take the strain off the jacks after the jacks have moved the framework to adjusted position. These wedges lie between the plate 23 and an abutment 25 which constitutes a part of the stool 20. Each wedge is provided at one end with a block 26 through which the threaded end of the other wedge extends, such threaded ends carrying the adjusting nuts 27, 27. By adjusting the nuts, the combined thickness of the wedges may be varied so that they fit the space between the plate 23 and the

abutment 25, thus blocking the framework in its adjusted position. In order to secure the plate 23 rigidly in position with respect to the stool therebeneath, the four clamping bolts 26' are employed, such bolts being secured at their lower ends in the stool and being provided at their upper ends with the nuts 27'.

Means are also provided, as indicated in Figs. 6 and 7, for leveling up the track independent of the adjustment of the frame, as above described. This leveling means preferably takes the shape of a plurality of sets of wedges arranged at suitable intervals 15 along the track between such track and the track beams 11 therebeneath. Each adjusting device comprises a pair of members 28, 29 having opposing inclined surfaces and pivoted together by the pin 30. The end of 20 one of these members carries the bolt 31 which extends through the forked end 32 of the other member and is provided with an adjusting nut 33. By screwing in the nut 33, the wedge members are moved over each 25 other so that their total thickness is increased, thus moving the rail 4 upward the desired amount. Clamping means are provided in the form of the pairs of bolts 34 extending through slots 35 in the clamping 30 members and through the flanges of the rail 4 and of the track beam 11. By the use of these devices, the track may be kept perfectly level at all times.

Fig. 8 shows a modification of the track adjusting means in which the circular wedges of Figs. 6 and 7 are replaced by the straight wedges 36, 37 lying between the rails 4 and track beams 11. Bolts extending through the slot 38 in the wedges and through the 40 flanges of the rails and track beams serve to lock the parts in adjusted position. Tables 5, 5 are locked tightly together as indicated in this figure, and a drain trough 39 is provided extending transversely of the space 45 40 between the cars in order to conduct away any abrasive which may penetrate between the ends of the cars, such trough discharging into the drain troughs 41 at the sides of the track. These troughs and the troughs 50 42 serve to return the used abrasive which is discharged from the sides of the tables back to the grading apparatus.

The framework which supports the machines and tracks may also be utilized as a 55 support for the rails 43, 43, which carry the inner ends of the cranes 44, 44, the other end of the crane beams being carried by the rails 45, 45 supported from the side walls 1, 1 of the building. These cranes are utilized for 60 bringing the grinding machine units to position and removing them. The return tracks 46, 46 for the tables are supported upon a framework 47, at each side of the building, such framework being independent of that 65 which carries the work tracks 4, 4 and the

surfacing machines. It will be seen that all parts of the apparatus may be readily adjusted to secure alignment without any discontinuance of the operation, and that the structure is a rigid one in which the liability 70 to get out of alignment is reduced to a minimum because of the independence of the supporting means with respect to the building structure. This makes for accuracy in the surfacing operations and reduces break- 75 age in the product.

Fig. 9 illustrates a modification of the structure of Figs. 4 and 5, wherein provision is made between the stools 20 and girders 10 for expansion and contraction incident to temperature changes. The structure here is the same throughout as in Figs. 4 and 5 except that a pair of plates 48, 49 are substituted for the plate 23 of the Figs. 4 and 5 construction with a series of rollers 50 between the opposing faces of the plates. This permits the structure carried by the stools to move backward and forward under temperature conditions independent of the stools.

What I claim is:

1. In combination in continuous sheet surfacing apparatus, a track, a series of sheet supporting cars mounted on the track for movement therealong, a series of surfacing machines arranged along the track provided with driven runners positioned above the sheets on the cars, a supporting framework carrying the track and said machines, a rigid foundation beneath the framework, and adjustable supporting devices intermediate the foundation and said framework arranged in series longitudinally and laterally thereof whereby any part of the framework may be adjusted vertically to bring the parts carried thereby into alignment. 90

2. In combination in continuous sheet surfacing apparatus, a track, a series of sheet supporting cars mounted on the track for movement therealong, a series of surfacing machines arranged along the track provided with driven runners positioned above the sheets on the cars, a supporting framework carrying the track and said machines, adjusting devices arranged in series along the track between the framework and track for aligning the track, a rigid foundation beneath the framework, and adjustable supporting devices intermediate the foundation and said framework arranged in series longitudinally and laterally thereof whereby any part of the framework may be adjusted vertically to bring the parts carried thereby into alignment. 105

3. In combination in continuous sheet surfacing apparatus, a track, a series of sheet supporting cars mounted on the track for movement therealong, a series of surfacing machines arranged along the track provided with driven runners positioned above the sheets on the cars, a supporting framework 110

carrying the track and said machines, sets of adjusting wedges arranged in series along the track between the framework and track for aligning the track, a rigid foundation beneath the framework, and adjustable supporting devices intermediate the foundation and said framework arranged in series longitudinally and laterally thereof whereby any part of the framework may be adjusted vertically to bring the parts carried thereby into alignment.

4. In combination in continuous sheet surfacing apparatus, a track, a series of sheet supporting cars mounted on the track for movement therealong, a series of surfacing machines arranged along the track provided with driven runners positioned above the sheets on the cars, a supporting framework carrying the track and said machines, a rigid foundation beneath the framework, and adjustable supporting devices intermediate the foundation and said framework arranged in series longitudinally and laterally thereof whereby any part of the framework may be adjusted vertically to bring the parts carried thereby into alignment, said devices comprising jacks for giving the necessary lifting action, and blocking means for taking the weight after the lifting action by the jacks.

5. In combination in continuous sheet surfacing apparatus, a track, a series of sheet supporting cars mounted on the track for movement therealong, a series of surfacing machines arranged along the track provided with driven runners positioned above the sheets on the cars, a supporting framework carrying the track and said machines, a rigid foundation beneath the framework, and adjustable supporting devices intermediate the foundation and said framework arranged in series longitudinally and laterally thereof whereby any part of the framework may be adjusted vertically to bring the parts carried thereby into alignment, said devices comprising jacks for giving the necessary lifting action, and blocking means in the form of wedges for taking the weight after the lifting action by the jacks.

In testimony whereof, I have hereunto subscribed my name this 20th day of May, 1930.

JOHN H. FOX.
